TOY ANIMAL FIGURE

Esther R. Kovac, 3415 N. Huson St., Tacoma, Wash.

Filed May 7, 1962, Ser. No. 69,994

Term of patent 14 years

(Cl. D34—2)

I claim:

The ornamental design for a toy animal figure, substantially as shown.
